UNITED STATES PATENT OFFICE

135,830

DESIGN FOR A LAMP

Samuel L. Dinkelspiel, Chicago, Ill.

Application November 16, 1942, Serial No. 103,794

Term of patent 3½ years

To all whom it may concern:

Be it known that I, Samuel L. Dinkelspiel, a citizen of the United States and resident of Chicago, in the county of Cook and State of Illinois, have invented a new, original, and ornamental Design for a Lamp, of which the following is a specification, reference being had to the accompanying drawing, which forms a part thereof.

The figure is a side elevation of a lamp showing my new design.

The article is of circular cross section throughout its height.

I claim:

The ornamental design for a lamp, substantially as shown and described.

SAMUEL L. DINKELSPIEL.
